[57] CLAIM

The ornamental design for a electrically heated garment, as shown and described.

DESCRIPTION

FIG. 1 is a top, front, left side perspective view in an alternate position of the electrically heated garment of the present invention;

FIG. 2 is a front elevational view of the electrically heated garment of FIG. 1;

FIG. 3 is a left side elevational view of the electrically heated garment of FIG. 1;

FIG. 4 is a top plan view of the electrically heated garment of FIG. 1;

FIG. 5 is a bottom plan view of the electrically heated garment of FIG. 1;

FIG. 6 is a rear elevational view of the electrically heated garment of FIG. 1; and,

FIG. 7 is a right side elevational view of the electrically heated garment of FIG. 1.

The broken lines in FIGS. 1–3 are understood to represent stitching.
